DESIGN FOR A DRESS OR SIMILAR ARTICLE

Herman Beispel, New York, N. Y.

Application February 10, 1941, Serial No. 98,880

Term of patent 3½ years

To all whom it may concern:

Be it known that I, Herman Beispel, a citizen of the United States, residing in the city, county, and State of New York, have invented a new, original, and ornamental Design for a Dress or Similar Article, of which the following is a specification, reference being had to the accompanying drawing, forming part thereof.

Fig. 1 is a front view of a dress showing my design;

Fig. 2 is a rear view of the dress shown in Fig. 1;

Fig. 3 is an enlarged fragmentary view of the dress shown in Fig. 1, illustrating the open-work embroidery thereon in detail;

Fig. 4 is an enlarged fragmentary view of the dress shown in Figs. 1 and 2, illustrating in detail the embroidery on the cuffs.

The characteristic feature of my design resides in the combination on the dress disclosed of the specific embroidery along the front of the dress and about the cuffs, in association with an insert of contrasting material along the front of the skirt portion and about the neckline, and the pleated shoulder portions and waistline portion, all as shown.

I claim:

The ornamental design for a dress or similar article, as shown and described.

HERMAN BEISPEL.
